CLAIM

The ornamental design for a ceiling fan blade, as shown and described.

DESCRIPTION

FIG. 1 is a top perspective view of a ceiling fan blade shown in the environment of a ceiling fan, showing our new design; FIG. 2 is a bottom perspective view of the ceiling fan blade of FIG. 1, with the ceiling fan environment removed;

FIG. 3 is a top view thereof;

FIG. 4 is a bottom view thereof;

FIG. 5 is a left side view thereof;

FIG. 6 is a right side view thereof;

FIG. 7 is a bottom perspective, front side view thereof; and, FIG. 8 is a rear view thereof.

Portions of the ceiling fan blade and the ceiling fan environment shown in broken lines form no part of the claimed design.

1 Claim, 6 Drawing Sheets
